ARCH SUPPORT

Application filed January 7, 1932. Serial No. 585,188.

This invention relates to devices for correcting the arches of the foot which have assumed abnormal positions and for strengthening and healing the muscles and tendons thereof.

The arches of the human foot have a very definite natural position peculiar to the individual, and when the elements which tie together the bony structure of the foot become weakened the arches assume a permanent position below their normal disposition and the individual suffers what is commonly known as fallen arches. As the bones of the foot articulate in this subnormal position the muscles and ligaments are overtaxed and become weakened. If this condition is not remedied and the person continues to sustain his weight upon his feet, the affect upon his arches is cumulative and in time will cause the individual much suffering. It is the principal object of the present invention to provide means which will support the bones of the foot in their natural positions, and thereby permit the muscles and tendons of the foot to regain their normal strength.

The invention has for a further object to provide an arch support which sustains all portions of the arch in their natural position, and at the same time acts to absorb all excessive pressure over and above that caused by the weight of the body.

The object of the invention is further to provide an arch support which conforms to an accurate impression of the bottom surface of the individual foot and is itself supported at all points by reason of its accurate conformity to the inner face of the inner sole of the shoe.

A further object of the invention is to provide a support capable of being readily shaped to correct any maladjustment of any or all of the various arch structures of the foot or the alignment of the heel.

A further object of the invention is to provide in an arch support means to eliminate irritation of the portions of the foot caused by rubbing contact with the shoe, thereby to prevent the formation of callouses and the like.

50 Other objects and features of the invention

will more fully appear from the following description in connection with the accompanying drawings and will be particularly pointed out in the claims.

The invention comprises essentially a supporting member which transfers the pressure of the sole of the shoe to the sole of the foot in a manner to correctly support the arches. It is constructed of special material which yields upon the application of excessive pressure, but is sufficiently resistant to retain its original conformation, while sustaining the weight of the body. As will herein-after more fully appear, the support is accurately shaped to conform to the foot by a special process. When the support has been given its correct shape in order to give it a suitable finished appearance, its top and bottom face are covered with fabric of soft leather or any other material of similar character.

The effectiveness of the present invention is more clearly presented by first briefly discussing the structure of the human foot. The skeleton of the foot viewed from one side presents a generally flat triangular form having its long side at the base of the foot. The two upwardly-extending sides of the triangle are composed of a series of bones which receive the weight of the body at their apex and which articulate when walking. This jointed bone structure forms the principal or plantar arch of the foot. This arch structure is maintained in its proper position and the various elements thereof are restrained longitudinally and transversely by numerous muscles, tendons and ligaments, the most important of which is the plantar ligament which connects the two lower points of the arch.

When the muscles and tendons of the foot become weakened or diseased, the arch tends to lower, due to the weight of the body, thereby creating an abnormal condition. To correct this condition, the arch must be gently and firmly supported in its natural position and maintained in that position in order to permit the muscles and tendons to regain their former strength. The present invention accomplishes this result in a very effec-

tive manner. The particular construction of the arch support embodying the invention affords a firm support which corrects the mal-adjustment of the arch, and furthermore has 5 a surface which will yield at any particular point where an abnormal pressure arises, such for instance, as the abnormal pressure caused by the bulging of a muscle.

The present invention contemplates the 10 production of a suitable corrective appliance for each foot of the particular individual for whose use it is adapted and comprises the production of a reenforcing device for the articulated members of the foot which 15 presents an upper surface conforming to the contour of the undistended normal sole of the foot, and an under surface conforming to the surface of the inner sole of the shoe, with a reenforcement therebetween of material having sufficient resilience to withstand 20 the normal pressure of the foot and yieldable in any portion in response to abnormal pressure applied to the upper surface thereof.

The term "insole" is used therein as defining 25 the corrective device which is adapted to be inserted into the shoe which the individual uses and which rests upon the inner sole of the shoe. The term "inner sole" is used herein to define the inner sole portion of the shoe which may be directly secured to the outer sole or which may be indirectly secured thereto by a welt.

The character of the arch support is such that a local displacement of the surface of the arch may take place, while the remaining area thereof maintains the bony structure of the foot in its corrected position. It is apparent, therefore, that an even pressure is maintained at all times throughout the entire area of the support, thereby eliminating the possibility of any irritation between the support and the bottom of the foot. The structure of the support is such that it is capable of sustaining the weight of the body and resists depression caused by a normal stress imposed thereon. When, however, a sudden shock or an abnormal pressure is applied to the foot, the support will yield and thereby avoid transmitting such shock to the tender pliant members of the foot. The action of the arch support when walking becomes a gentle massage of the foot permitting the free-play of all muscles and tendons which rapidly restores it to a normal healthy condition.

The present invention not only includes an insole of the character above described, but the method of producing the same which may be broadly described as the process of producing an insole for reenforcing articulated members of the foot which comprises producing from plastic material a model conforming to the undistended sole of the normal foot smoothly applying a thin sheet of fibrous material to the sole portion model

in such a manner as to conform thereto throughout its entire surface, detachably securing said sheet thereto, cementing upon the sheet of fibrous material a layer of suitable resilient material, then fashioning the upper surface thereof to conform to the surface contour of the inner sole of the shoe, and preferably cementing upon the surface thus formed a cover of pliable material permitting the inner sole thus formed to set firmly and finally removing the insole from the model. The insole thus formed is adapted when inserted in the shoe, therefore, to conform upon its under side to the contour of the inner sole of the shoe and its upper surface will conform strictly to the contour of the sole of the individual's foot in its normal undistended condition. By reason, therefore, of the flexibility of the sole of the shoe and of the resilient reenforcing member, the articulation of the foot will at all times be properly maintained whether the wearer of the shoe is sitting, standing or walking.

In the drawing:

Fig. 1 is a cross sectional view through the arch supporting insole in process of construction while applied to a model of the individual foot.

Fig. 2 is a cross sectional view of the arch supporting insole in the position it is worn within the shoe.

Fig. 3 is a top plan view of the support before it has received its finishing covers.

Fig. 4 is a section on line 4—4 Fig. 3.

Fig. 5 is a section on line 5—5 Fig. 3.

The drawing illustrates the several steps of the method above described for producing an individual insole having the characteristics above defined. Since the proper function of the device depends upon its accurate conformation to the contour of the sole of the foot when the elements of the foot are in their normal position, an impression or matrix of the foot is first taken. The matrix may be made in any suitable material which readily receives an impression. The matrix is then used to cast a model 1 of plaster of Paris or any other similar material suitable for the purpose. The finished model then bears the shape of the foot of the patient and is trimmed along its periphery to the desired dimensions of the finished support. For convenience a model 1 is inverted as shown in Fig. 1 and a sheet of fabric 2, such as cheese cloth or material of similar nature is applied to the surface of the model by drawing its edges down over the sides thereof and cementing them thereto. The cloth then is given one or more coats of waterproof cement which is allowed to harden. The body portion 3 of the support is then cemented to the fabric 2. The material out of which the body portion is made must have the characteristics above specified. A sheet of cork in its natural form or a sheet of agglomerated

resilient granulated material such as granulated cork has been found to be a satisfactory material. A portion 3 of the sheet then is cut to a generally triangular shape and of a length to extend throughout substantially the distance between the points of support of the arch. The triangular body portion then is skived or filed roughly to the proper shape to fill the depression of the main or plantar arch with one of its faces fitting the inner surface of the sole of the shoe, and its other face conforming to the face of the model. The body portion 3 then is applied to the fabric sheet 2 which has been previously secured to the model, and which has been coated with another layer of cement. Sufficient pressure then is applied to cause the portion 3 to assume the exact form of the model.

If it is necessary to correct other portions of the foot besides the plantar arch, for instance, the transverse or metatarsal arch, or to correct the alignment of the heel, additional supporting members may be provided. The support shown in Fig. 1 is provided with a pad or "rise" 4 adapted to correct the alignment of the heel and in addition a pad or "rise" 5 is cut and shaped to fill the depression of the metatarsal arch. The pad or "rise" 4 acting upon the heel preferably is made of the same material as the section 3 and is skived to proper dimensions and cemented to the section 3 in position to form a smooth curved contour therewith. The pad or "rise" 5 is of similar material and shaped to correct the metatarsal arch and cemented to the forepart of the section 3 in correct position to sustain the arch in its natural position.

The assembled arch support having the pads 4 and 5 attached thereto is then applied to the model and cemented to the fabric 2 thereon under pressure in the manner above set forth in connection with the body portion 3 when used without the additional rises. The cement is then allowed to harden and the arch support is stripped from the model by cutting or tearing the fabric 2 at the upper peripheral edge of the model.

The arch support then is inverted and placed in position within the shoe to determine whether its bottom face conforms to the inner surface of the shoe sole. If the fit is not proper, the support is filed and skived until its whole area bears evenly upon the inner sole of the shoe. Before putting on the finishing top and bottom layers of fabric the support may be perforated throughout its area as by means of the series of apertures 6. These apertures may be formed in the support before it is applied to the model if desired. The perforations provide beneficial ventilation within the shoe which aids in the normal respiration through the pores of the skin and they also serve to provide a more effective resilient charac-

ter to the material of the body portion of the device.

After the support has received its final conformation a layer of fabric 7, such as khaki or material of similar character is cemented to the bottom face thereof and trimmed neatly to the edge. The upper surface desirably is provided with a layer 8 of soft leather such as calfskin or suede. After trimming the layer of leather on the top surface the completed support again is applied to the model where it is allowed to harden thoroughly. When the completed arch-supporting insole is inserted in the shoe 9, its upper face presents a surface accurately conforming to the sole of the normal foot and acting to apply exactly the proper corrective pressure to the deformed portions of the foot.

One of the important features of the invention is the fact that every portion of the foot is supported in its correct position and maintained in that position since there is present at every point throughout the area thereof exactly the right amount of filling between the foot and all portions of the shoe. This feature has the effect of restoring the arch by supporting the weakened elements of the foot in a natural and gentle manner, which results in time in restoring the elements of the foot to their normal condition.

By securing to the rear end portion of the material for reenforcing the arch a pad of suitable material fashioned to raise the portion of a heel which has been displaced from its normal position, the alignment of the heel can be corrected, thereby further aiding and restoring the arch to its normal position.

In instances where a misplacement of the anterior or metatarsal arch has occurred, a pad of suitable material fashioned to restore the displaced arch to normal position not only aids the muscles and tendons in restoring the arch to its normal position, but it also so corrects the skeleton structure of the foot as to prevent undue displacement of the joints and consequent friction with the upper of the shoe which would result in callouses or corns, inasmuch as the formation of callouses is caused by rubbing contact with the portion of the shoe which is not properly adjusted to the foot. Where corns or bunions are found upon the bottom of the foot, the pad is correctly positioned to press gently but firmly upon the corn or bunion which will reduce the friction between the skin and the insole to a sufficient extent not only to prevent increase upon the thickness of the corn or bunion, but eventually to restore the skin to normal condition.

Such a method is the most effective method to restore arches of the foot which have lowered or to correct misalignment of any of the bony structures thereof. Much of the prac-

tices heretofore in evidence have been based upon entirely different principles involving the use of a ready made or "stock" arch support made of metal or other rigid material. 5 One of the chief objections to using such an arch support is the practical impossibility of shaping the support to accurately fit the individual foot. An arch supporting insole constructed under the principles of the present invention is exceedingly comfortable to wear owing to its yielding character as above described, and produces a very beneficial massaging action while walking.

Having thus described the invention, what 15 is claimed as new, and desired to be secured by Letters Patent, is:

1. The process of producing an insole for reenforcing articulated members of the foot which comprises producing from plastic material a model conforming to the undistended sole of an individual's normal foot, smoothly applying light fabric to the sole portion of said model throughout its entire area and detachably securing margins of the same to 25 said model, cementing a sheet of resilient material to said fabric, fashioning the upper surface thereof while secured to the model to conform to the surface contour of the inner sole of the shoe, cementing a covering of 30 pliable material to said resilient material permitting the cement to harden while the insole is secured to said model, and detaching the insole thus formed from the model.

2. The process for producing an insole for 35 reenforcing articulated members of the foot which comprises producing from plastic material a model conforming to the undistended sole of an individual's normal foot, smoothly applying a light fabric to the sole portion of said model throughout its entire area and detachably securing the margin of the same to said model, cementing a body of resilient reenforcing material to said fabric, fashioning the upper surface thereof while 40 secured to the model to conform to the contour of the inner sole of the shoe, skiving the heel portion of said body and cementing thereto a reenforcing member corrective of misalignment of the heel and cementing a 45 covering of pliable material to said body and pad, permitting cement to harden while the insole is applied to the model, and detaching the insole from the model.

3. The process for producing an insole for 50 reenforcing articulated members of the foot which comprises producing from plastic material a model conforming to the undistended sole of an individual's normal foot, smoothly applying a light fabric to the sole portion 55 of said model throughout its entire area and detachably securing the margin of the same to said model, cementing a body of resilient reenforcing material to said fabric, fashioning the upper surface thereof while secured 60 to the model to conform to the contour of the

inner sole of the shoe, applying to the front end portions of said body a pad fashioned to compensate for a misplaced anterior or metatarsal arch, cementing the covering of pliable material to said reenforcing members, 70 permitting the cement to harden while the fabricated insole is secured to said model and detaching the insole thus formed from the model, and applying to the upper surface thereof a covering of soft pliable material. 75

4. The process of producing an insole for reenforcing articulated members of the foot which comprises producing from plastic material a model conforming to the undistended sole of an individual's normal foot, smoothly applying a light fabric to the sole portion of the model throughout its entire area, detachably securing the margins of the same to said model, cementing a sheet of granulated cork composition to said fabric, skiving 80 the upper surface thereof while secured to the model to conform to the surface contour of the inner sole of the shoe, cementing a covering of pliable material to the upper surface of the fashioned cork composition, permitting the cement to harden while the insole is secured to the model, and finally detaching the insole thus formed from the model.

In testimony whereof, I have signed my 95 name to this specification.

JEAN G. MITCHIE.
